UNITED STATES PATENT OFFICE.

CLAUD W. COBURN, OF RAPID CITY, SOUTH DAKOTA.

COMBINATION TOOL.

Application filed October 19, 1925. Serial No. 63,445.

This invention relates to a combination tool, and has for its object to provide a tool of this character which is well balanced and well adapted to carry out its manifold functions. More particularly, the invention relates to a combination tool which may be used as a hammer or steak pounder, as a pair of pliers or wire gripper, as a screw-driver or tack-puller, as a stove-lid lifter or grate shaker, or as a lifter for hot pans or containers.

A further object is to provide a tool having these advantages and capacities and which is of simple and durable construction, reliable and effective in operation, and easy and comparatively inexpensive to manufacture.

Other objects and advantages reside in certain novel features of the construction, arrangement, and combination of parts which will be hereinafter more fully described and particularly pointed out in the appended claim, reference being had to the accompanying drawings forming a part of this specification, and in which:

Fig. 1 is a perspective view showing one embodiment of the invention,

Fig. 2 is a view thereof in side elevation,

Fig. 3 is a plan view, and

Fig. 4 is a sectional view on the line 4—4 of Fig. 2.

Referring to the drawings it will be seen that the tool embodying the present invention provides a pair of closed handles, designated at 1 and 2, the handle 2 having a laterally offset portion 3 adapted to engage the handle 1 when the handles are brought together. The forward ends of the handles are pivotally connected to each other by means of a pivot bolt and nut 4, and on the opposite side from the pivot bolt from the handles 1 and 2 working heads, designated at 5 and 6 are provided. The working head 5 has a serrated impact face 7 which may be used as a steak pounder when the handles 1 and 2 are brought together. At such time the working head 6 engages the working head 5 so that a heavier hammer head is provided. As the handles 1 and 2 are engaged with each other due to the projection of the lateral offset 3 the handles 1 and 2 readily adapt the tool for use as a hammer

and permit the tool to be swung with facility in the same manner that a hammer is swung. The working heads 5 and 6 have co-operable 55 jaw faces 8 and 9 which enable the device to be used as a pair of pliers. The working head 6 is also shaped to provide a tongue engageable with the socket of a stove lid whereby the device may be used as a stove- 60 lid lifter.

The heads 5 and 6 are also provided with co-acting cutting edges 10 and 11, the cutting edge 11 being of V-shaped form. These cutting edges 10 and 11 enable the tool to be 65 used as a wire cutter.

The rear portion of the working head 6 has integrally formed therewith at the throat thereof a rectangular socket member 12 designed to engage the operating bar of the 70 grate to enable the tool to be used as a shaker for grates and which by being so disposed is out of the way when the tool is used for other purposes as well as increasing the compactness of the tool. The rear end of the 75 handle 1 is provided with V-shaped notch 15 which enables the tool to be used as a tack puller. The handle 2 has its rear end formed to provide the tip or bit of a screw-driver, as indicated at 16. The shank of the 80 screw-driver is provided by the handle 2. It is to be noted that the handle 1 is curved which facilitates the application of leverage to the tack to be pulled.

The working head 6 due to the curved 85 formation of its jaw face 9 is also adapted to coact with the jaw face 8 of the working head 5 to lift ordinary pans or other utensils.

A novel form of spring means is provided for normally spacing the jaw faces of the 90 working heads apart. This spring means includes an expanding coil spring 20 which is accommodated in complementary recesses 21 and 22 provided in the hub portions of the handles 1 and 2 adjacent the pivot thereof. The recesses 21 and 22 incline obliquely across the handles and this inclination enables the spring 20 to yieldably urge the jaw faces apart.

I claim:

A tool comprising a pair of elongated members each having a bar-like intermediate portion, the side faces of said portions abutting each other and the members being piv-

totally connected adjacent the forward ends of said bar-like portions and having flat opposed faces, and one of the members having an elongated rear end portion of increased width upon which the similar portion of the other member is adapted to engage when the same are brought together and form a com-

pact handle, each member terminating at its forward end in a jaw, said flat faces having complementary obliquely disposed recesses at a point adjacent the pivot connection therefor, and a coil spring in said recesses adapted for pressing the jaws apart.

CLAUD W. COBURN.
